CONVEYER

Edwin Archer Turner, New York, and Charles J. Surdy, Tuckahoe, N. Y., assignors, by mesne assignments, to The Standard Stoker Company Inc., (1922), New York, N. Y., a corporation of Delaware

Application June 27, 1936, Serial No. 87,622

6 Claims. (Cl. 198—15)

Our invention relates to conveyers and especially to conveyers of the type which are especially adaptable for service in the transfer of fuel from the tender to a locomotive firebox.

5 It is the principal object of our invention to provide improved means for supporting one end of a conveyer, such improved means consisting of a pivotally supported member which supports the aforesaid end of the conveyer in a manner to provide universal movement therefor.

10 A further object of our invention resides in the provision of such improved supporting means whereby the supported end of the conveyer is capable of universal movement with respect to the pivotally supported member as the latter swings about its axis.

15 A more specific object of our invention contemplates the provision of this novel support in a locomotive stoker conveying system and especially for use in a conveying system employing several conveyers having an offset relation therebetween.

20 These and other objects will become apparent as the following description of our invention is read in connection with the accompanying drawing wherein the invention has been illustrated in its embodiment in a locomotive stoker.

25 Fig. 1 of the drawing is a view partly in section and partly in elevation through adjacent portions of a locomotive and tender illustrating the improved conveyer embodied in a stoker mechanism;

30 Fig. 2 is a sectional view taken on the line 2—2 of Fig. 1 looking in the direction of the arrows; and

35 Fig. 3 is a sectional view taken on the line 3—3 of Fig. 1 looking in the direction of the arrows.

On this drawing, A is the locomotive, B the tender thereof and C a coupling member between the locomotive and tender. The locomotive A includes a boiler 10 having a backhead 11 on which is supported the fuel discharge conveyer 12 of the stoker mechanism S. At 13 is indicated the tank of the tender B and it is provided with a compartment 14 beneath the deck 15, the latter forming the bottom of the fuel bin 16.

40 The stoker mechanism S includes a conveyer 17 rigidly mounted on the tender within the compartment 14, the fuel discharge conveyer 12 which is rigidly attached to the backhead 11 of the locomotive boiler by means of brackets 18, 19, and an intermediate conveyer 20 between the conveyers 12 and 17. Comprising the conveyer 17 is a trough-like conduit 21 having an upwardly opening mouth 22 which registers with an ap-

erture 23 in the fuel bin floor 15. This aperture is covered by plates 24 which are slidable to form an opening 25 in various longitudinal relations with respect to the fuel bin 16 and through which opening the fuel falls into the conduit 21 upon a conveyer screw 26 therein. The conveyer screw 26 urges the fuel forwardly and cooperates with a toothed crusher 27 to reduce large lumps of fuel to a suitable size for efficient firing.

5 The intermediate conveyer 20 includes a conduit element 29 having a rearward end 30 which is disposed beneath the tubular discharge end 31 of the trough conduit 21 to receive fuel therefrom. Forward of its rearward end 30, the intermediate conduit element 29 is provided with a tubular portion 32 having a spherical flange 33 which is received in a spherical seat 34 of an elevating conduit 35, the latter comprising a portion of the inclined conveyer 12. A clamp 36 retains the spherical flange 33 in the seat 34 and these parts form a ball and socket joint 37 between the intermediate conduit element 29 and the elevating conduit 35. It will be observed that the ball and socket joint 37 permits angular movement between the conduits 29, 35 but maintains a constant longitudinal relation therebetween.

10 Within the conduit element 29 is a conveyer screw 38 which is connected by a universal joint 39 to the conveyer screw 40 of the elevating conduit 35. At its rearward end, the conveyer screw 38 has an operative connection, which may be in the form of a universal joint 41, with a stub shaft 42 journaled in the bearing 43 of the conduit element 29. The stub shaft 42 is connected by a universal joint 44 to an extensible and contractible shaft 45 which underlies the trough conduit 21 and is universally connected at 46 to the drive mechanism 47. The drive mechanism includes a gear 48 which is arranged to connect the conveyer screw 38 and the trough conveyer screw 26 to a power operated shaft 49 (Fig. 3). The gear 48 is meshed by a gear (not shown) secured to the power shaft 49.

15 The gear 48 is loosely mounted on a shaft 50 which is operatively connected to the trough conveyer screw 26. On one side, the gear 48 is provided with clutch teeth 51 which are arranged to be engaged by teeth 52 of a clutch element 53 slidably mounted on keys such as 54 of the shaft 50. The gear 48 has fixed thereto a gear 55 which has an operative connection with the extensible and contractible shaft 45. By this construction, the conveyer screws 26 and 38 operate together.

when the clutch teeth 51, 52 are in engagement. However, should foreign material, wedging between the flights of the conveyer screw 26 and the crusher 27, render the entire conveying mechanism inoperative, the clutch element 53 may be moved to the position shown in Fig. 1 whereby the conveyer screw 38 will continue to operate. Manual delivery of fuel into the upwardly open rearward end 30 of the intermediate conduit element 29 is effected by swinging open the hinged cover 56 in the tender deck 15 and also by moving the foremost plate 24 to the left.

The rearward end 30 of the conduit element 29 is supported in an improved and novel manner to provide for the necessary movement between the stoker units as articulation of the locomotive and tender occurs. On its under side, the rearward end of the conduit element 29 is provided with a circular lug 57 fitting into an opening 58 formed 20 in the bottom wall 59 of the saddle member 60. At each side of its bottom wall 59, the saddle member 60 is provided with an upstanding flange 61. A heavy round bar 62 passes through opposite upper ends of the flanges 61 and through the 25 lugs 63 which are formed on the upper forward portion of the tubular discharge end 31 of the trough conduit 21.

In this manner, the saddle member 60 and the rearward end of the conduit element 29 are pivotally supported from the trough conduit 21. By disposing the bar 62 at a considerable distance above the bottom wall 59 of the saddle member 60, the wall 59 and the rearward end 30 of the conduit element 29 will swing through a comparatively flat arc as relative fore and aft movement between the locomotive and tender occurs. Thus, the lower end of the conduit element 29 may be spaced closely to the trough conduit 21.

During operation of the locomotive and tender, the intermediate conveyer 20, by reason of its universal connection 31 with the inclined conveyer 12 and the novel support at the rearward end of the conduit element 29, provides for the necessary articulation between the conveyers 17, 40 12. When the locomotive and tender become separated a distance greater than that shown in Fig. 1, the circular lug 57 of the conduit element 29 draws the saddle member 60 forwardly about the axis of the bar 62; rearward movement of the saddle member 60 takes place when the distance 45 between the locomotive and tender is reduced, such as will occur upon coupling of additional cars. As shown, the saddle member 60 and the rearward end of conduit element 29 supported 50 by the saddle member are capable of movement 55 several inches in a forward or rearward direction.

When the locomotive and tender round curves, lateral displacement of the vehicles and conveyers 17, 12 will take place. In such instances, the intermediate conveyer 20 will flex laterally about the universal joint 31 and the axis of the circular lug 57. When the vehicles and conveyers 17, 12 move vertically with respect to each other, the rearward end of the intermediate conveyer 20 60 may move about a horizontal transverse axis because the under side of the conduit element 29 adjacent the lug 57 is slightly spherical in shape. The opening 58 is also elongated slightly to permit such movement of the intermediate conveyer. 65 As shown in Figs. 2 and 3, the circular lug 57 fits closely adjacent the lateral sides of the slightly elongated opening 58 whereby movement of the conduit element 29 about its longitudinal axis is restrained.

70 From the foregoing, it will be apparent that a

novel support for the rearward end of the intermediate conveyer 20 has been provided, such support providing ample flexure and extensibility between the conveyers 17 and 20 when the locomotive and tender are rounding curves, crossing 5 switches and turntables or upon sudden stops and starts of the vehicles.

We claim the following as new and useful:

1. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, means for supporting the last named end of said conveyer on such vehicle, said means including a member pivotally supported on such vehicle to swing on a horizontal transverse axis only, the last named end of said conveyer being pivotally supported on said member for movement about a vertical axis, and means restraining axial rotation of said conveyer.

2. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, means for supporting the last named end of said conveyer on such vehicle, said means including a member pivotally supported on such vehicle to swing on a horizontal transverse axis only, the last named end of said conveyer being pivotally supported on said member for movement about a vertical axis, and means restraining axial rotation of said conveyer.

3. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, means for supporting the last named end of said conveyer on such vehicle, said means including a member pivotally supported on such vehicle to swing on a horizontal transverse axis only, the last named end of said conveyer being pivotally supported on said member for movement about vertical and transverse horizontal axes with respect to said member, and means restraining axial rotation of said conveyer.

4. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, and means for supporting the last named end of said conveyer on such vehicle, said means including a saddle member provided with a bottom wall, the last named end of said conveyer being pivotally supported on said bottom wall for movement about a vertical axis, and means for pivotally supporting said saddle member for movement about a horizontal transverse axis only, the axis of said saddle member being at a sufficient distance above the bottom wall thereof whereby said bottom wall will swing fore and aft.

with respect to said vehicle through a relatively flat arc.

5. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, and means for supporting the last named end of said conveyer on such vehicle, said means including a saddle member provided with a bottom wall, the last named end of said conveyer being pivotally supported on said bottom wall for movement about a transverse horizontal axis with respect to the bottom wall of said saddle member, and means for pivotally supporting said saddle member for movement about a horizontal transverse axis only, the axis of said saddle member being at a sufficient distance above the bottom wall thereof whereby said bottom wall will swing fore and aft with respect to said vehicle through a relatively flat arc.

6. In an intercoupled locomotive and tender, a conveyer of constant length extending between the locomotive and tender, one end of said conveyer being flexibly supported on one of said vehicles and having an unvarying longitudinal relation therewith, the opposite end of said conveyer being disposed on the other of said intercoupled vehicles, and means for supporting the last named end of said conveyer on such vehicle, said means including a saddle member provided with a bottom wall, the last named end of said conveyer being pivotally supported on said bottom wall for movement about vertical and transverse horizontal axes with respect to the bottom wall of said saddle member, and means for pivotally supporting said saddle member for movement about a horizontal transverse axis only, the axis of said saddle member being at a sufficient distance above the bottom wall thereof whereby said bottom wall will swing fore and aft with respect to said vehicle through a relatively flat arc.
